UNITED STATES PATENT OFFICE.

DAVID B. REEVE, OF NEW YORK, N. Y.

SEAL-PADLOCK.

SPECIFICATION forming part of Letters Patent No. 308,987, dated December 9, 1884.

Application filed May 8, 1884. (No model.)

To all whom it may concern:

Be it known that I, DAVID B. REEVE, of the city, county, and State of New York, have invented a new and Improved Seal-Padlock, 5 of which the following is a full, clear, and exact description.

The object of my invention is to provide a new and improved padlock which is adapted to receive a seal card or ticket, and cannot 10 be opened without destroying or mutilating the said ticket.

The invention consists in a padlock provided in its top with a slot, through which a ticket or card can be passed into the casing, 15 which card covers an opening in the front of the casing, so that if the shackle is to be released the card must be cut or destroyed to permit pushing to one side the locking-hook in the lock. A slide covers the slot in the 20 top of the casing, and the slide is locked in place by the shackle.

Reference is to be had to the accompanying drawings, forming a part of this specification, in which similar letters of reference indicate 25 corresponding parts in all the figures.

Figure 1 is a side view of my improved padlock. Fig. 2 is a plan view of the same. Fig. 3 is a face view, the lock being closed and the face-plate removed. Fig. 4 is a cross-sectional elevation of the same on the line $x-x$, Fig. 3. Fig. 5 is a plan view of the slide.

In the padlock-casing A the usual shackle, B, is pivoted, and the lock is provided with a beveled hook, C, which is pressed by a spring, D, toward one side of the casing, so 35 that it will snap into the notch α in the shackle B when the shackle is swung into the casing. A longitudinal slot, E, is formed in the top of the casing, along the front side, F, of the casing, and through the said slot a seal card or ticket, G, is passed into the casing, which ticket shows through an opening, H, in the front F. On the top of the casing a slide, J, is held, said slide being provided at one end 40 with a slot, K, and an upwardly-bent wing part, L, adjoining the slot K, and on the end of the slide. The opposite end of the slide is bent to fit against the bent end of the top of the casing. The slide is below the pivoted 45 end of the shackle. A prong, M, is formed on the under side of the top of the casing, against which prong the upper end of the hook C rests when thrown toward the side of the casing as far as possible.

The lock is applied and used in the following manner: The slide J is withdrawn, as shown in Fig. 1, to open the slot E, the ticket or card G is passed through the slot E into the casing, the slide J is then pushed back and the shackle is swung down, and the hook end 50 of the same passes through the slot K in the slide and into the casing, thereby pressing back the hook C, which then snaps outward and catches the shackle. The shackle holds the slide J, thus preventing removal of the 55 same. The shackle cannot be released, as the ticket G covers the only opening through which access can be had to the spring-hook C.

In order to open the lock, the ticket or card G must be pierced or cut to permit passing 70 some implement through it to swing the hook C from the shackle. The ticket is thus destroyed, showing the lock has been opened.

The above-described lock can be used like any ordinary padlock.

Having thus described my invention, I claim as new and desire to secure by Letters Patent—

1. In a seal-padlock, the combination, with the casing provided with a slot in its top and a hinged shackle, of a slide having an opening for the passage of the free end of the shackle, substantially as herein shown and described, whereby provision is made for closing the slot in the casing and locking the slide in position, as set forth.

2. In a seal-padlock, the combination, with the casing A, provided with a slot, E, in its top, and an opening, H, in its front, and the hinged shackle B, of the slide J, provided with the slot K, substantially as and for the purpose set forth.

3. The combination, with a padlock having a slot in its top, of the slide J, having a slot, K, and an upwardly-projecting part, L, at one end, substantially as herein shown and described.

4. The combination, with a padlock-case having a large opening in its front and a slot on its top, of the slide J on the top of the casing, which slide is provided with a slot, K, at one end, the hook C, the spring D, and the shackle B, substantially as herein shown and described.

DAVID B. REEVE.
